CLAIM

The ornamental design for a low rocking chair, as shown.

DESCRIPTION

FIG. 1 is a top left front perspective view of the low rocking chair showing our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a top left back perspective view of the low rocking chair in a folded state;

FIG. 9 is a right side view thereof;

FIG. 10 is a left side view thereof;

FIG. 11 is a front view thereof;

FIG. 12 is a back view thereof;

FIG. 13 is a top view thereof; and,

FIG. 14 is a bottom view thereof.

The dotted lines in the figures do not form any part of the claimed design for the low rocking chair.
